UNITED STATES PATENT OFFICE

RALPH K. MERRILL, OF GRAND RAPIDS, MICHIGAN, ASSIGNOR TO AMERICAN SEATING COMPANY, OF GRAND RAPIDS, MICHIGAN, A CORPORATION OF NEW JERSEY

FURNITURE CONSTRUCTION

Application filed April 17, 1929. Serial No. 355,708.

This invention relates to furniture construction.

The main objects of this invention are to provide an improved construction of table desk in which a center rib is used in place of a depending apron around the marginal edges; to provide an improved construction which secures a maximum of knee room for the user thereof and is therefore especially 5 suitable for kindergartens; and to provide an improved construction of supporting standard which can be fabricated from relatively light-weight sheet metal but which will be rigid and steady.

15 An illustrative embodiment of this invention is shown in the accompanying drawings, in which:

Fig. 1 is a view in end elevation of my improved table desk.

20 Fig. 2 is a sectional view taken on the line 2—2 of Fig. 1.

Fig. 3 is a fragmentary sectional view taken on the line 3—3 of Fig. 1.

25 Fig. 4 is a fragmentary thin sectional view taken on the line 4—4 of Fig. 3.

In the construction shown in the drawings, my improved table desk comprises a rectangular shaped horizontally disposed table top 1 supported by vertically disposed end 30 standards 2 attached to the under side thereof of adjacent the ends of said top. These standards are of identical construction, merely being made in rights and lefts, therefore the particular description of one standard 35 will suffice for both.

The inner side of the standard 2 closely adjacent the table top 1 is provided with an inwardly facing U-shaped bracket clip 3 which embraces the abutting end of a longitudinally extending bracing rib 4. The rib 4 is rectangular in cross section and disposed in vertical edgewise position with the top edge 5 thereof abutting against the under side of the table top 1. Bolts 6 and 7 pass 40 through the clip 3 and through the end of the rib 4 which is embraced thereby for securing the rib in position in snugly abutting relationship against the supporting standards 2.

50 Means are provided for securing the brac-

ing rib 4 in abutting relationship against the under side of the table top 1 and comprise Z-clips 8 and 9 which have one arm thereof secured by screws 10 and 11 respectively to the table top and the other arm thereof extending into kerfs 12 and 13 formed in the opposite sides of the rib 4.

The end standards 2 are fabricated from a pair of relatively light-weight sheet metal strips 14 and 15 disposed in spaced parallel 60 registering relation with their lateral marginal edges spot welded or otherwise suitably secured to vertically disposed semi-tubular post members 16 and 17. The strips 14 and 15 have rectangular shaped panel portions 18 and 19 respectively depressed inwardly in registry so as to contact and these contacting panels are spot welded or otherwise suitably secured together, preferably at the points 20, 21, 22, 23 and 24, these points being in the 65 middle and at the four corners of the contacting panel portions.

The semi-tubular member 16 is provided with a supporting foot 25 which has its upper end 26 telescoped a short distance into the 75 lower end of member 16 and secured thereto, as by spot welding. The lower end of the member 17 is provided with a supporting foot 27, the upper end of which embraces and is secured to the member 17 by spot welding or 80 the like.

The upper end of the supporting standard 2 has a furniture attaching bracket 28 spot welded or otherwise suitably secured thereto which is provided with a horizontally 85 disposed flange 29 through which a series of apertures 30 are formed. Screws 31 are provided to pass through the apertures 30 for securing the flange and supporting standard 90 to the underside of the table top 1.

In the use of this device, it is particularly suitable for kindergartens in which instances the table top is from eighteen to twenty-four inches from the floor. By eliminating the usual marginal depending apron present in 95 structures of this character, a maximum amount of room is provided for the knees of the children.

Extreme rigidity is secured by having the top edge of the bracing rib 4 abutting against 100

and secured firmly to the under side of the table top and its opposite ends embraced by and firmly secured to the inwardly facing U-shaped clips 3.

- 6 8 R rigidity of the end standards 2 is secured by spot welding the contacting depressed panel portions 18 and 19 together, which eliminates relative shifting of the sheet metal strips 14 and 15.
- 10 10 Although but one specific embodiment of this invention has been herein shown and described, it will be understood that numerous details of the construction shown may be altered or omitted without departing from the spirit of this invention as defined by the following claims.
- 15 15

I claim:

- 1. In metal structure of the character specified, a standard comprising a pair of sheet metal strips disposed in parallel relation with their marginal edge portions spaced apart and the intermediate portions pressed inwardly and connected to provide a panel, post members connected to opposite marginal edges of the strips and closing the space therebetween, a foot attached to the lower end of each post member, a bracket at the top and outer side of the standard and attached to the post members and outer strip, and a U-shaped clip at the top and inner side of the standard and attached to the inner strip.
- 20 20
- 2. The combination with a table top and a rib secured to the bottom side thereof, of a standard—one at each end of the rib—abutting the bottom side of the table top and end of the rib and attached thereto, said standard comprising a pair of sheet metal strips having their marginal edge portions spaced apart and the intermediate portions pressed in-
- 25 25
- 30 30
- 35 35
- 40 40
- 45 45
- 50 50

In testimony whereof I have hereunto set my hand at Grand Rapids, Michigan this 15th day of April, 1929.

RALPH K. MERRILL.
